UNITED STATES PATENT OFFICE.

THOMAS W. ALLEN AND LON A. WYATT, OF MEMPHIS, TENNESSEE.

BOX-CAR-DOOR LATCH.

Application filed April 30, 1924. Serial No. 709,984.

To all whom it may concern:

Be it known that we, THOMAS W. ALLEN and LON A. WYATT, citizens of the United States, and residents of Memphis, in the county of Shelby and State of Tennessee, have invented certain new and useful Improvements in Box-Car-Door Latches, of which the following is a specification.

Our invention relates to improvements in latches or retaining devices for the doors of freight cars, and it consists in the combinations, constructions and arrangements herein described and claimed.

More specifically, our invention is a latch which is adapted to be applied to a freight car door of ordinary construction and which then affords facilities for holding the car door either in open or closed position securely, although releasably.

An object of the invention is to obviate the necessity of providing the usual fastening cleats for securing a car door in closed position at the rearward edge of the car door, our invention comprising latching means for securing the car door to the car body so that a car door cannot readily be pried loose from or forced away from the car body at the rearward edge of the car door.

A further object of our invention is to provide a latch of simplified construction which comprises a movable latch bolt adapted to be carried by the car door and inherently actuated means urging the latch bolt continuously toward latching position.

A further object of our invention is to provide a latch for freight car doors which comprises a latch bolt which is adapted to cooperate with elements on the car body to releasably hold the car door in either closed position or open position when said latch bolt has been applied to the car door adjacent to the lower end of the latter and in position to be conveniently manipulated by a workman who is standing on the ground alongside of the car.

A still further object of the invention is to provide a latch of the character described which is adapted to be applied to the door of a freight car and which affords facilities for holding the door either in closed or open position in such manner that the stresses on the latch when the latter is in latching position will be effectively resisted without likelihood of breakage of any of the parts of the latch.

Other objects and advantages will be apparent from the following description, considered in conjunction with the accompanying drawings, in which—

Figure 1 is a side elevation showing a portion of a freight car equipped with a latch embodying our invention.

Figure 2 is a section substantially along the line 2—2 of Figure 1.

Figure 3 is a section substantially along the line 3—3 of Figure 1, and

Figure 4 is a section substantially along the line 4—4 of Figure 1.

In Figure 1, we show a portion of the body of a freight car 1 of ordinary construction. This freight car is provided with the usual opening in the side thereof and has a horizontally slideable door 3 movable to and from position to close the opening. The door 3 may be supported in any suitable known manner, as for example by means of the door hangers 4 at the upper end of the door cooperating with the horizontal rail 5 which is carried by the side wall of the car body at the upper end of the latter and the horizontal series of spaced retaining and guiding brackets 6 secured on the side wall of the car body in position to engage with the lower edge portion of the door. The door 3 also may be slightly spaced from the outer face of the side wall of the car body during its movement to open position by a horizontal bar 6' which is secured to the side wall of the car body adjacent to the lower end of the latter.

The car body ordinarily is provided with vertical posts, such as that indicated at 7, secured to the side wall against the inner face thereof and at opposite sides of the opening in the side of the car body.

The parts described so far are ordinary in construction and form no part of our invention except in so far as they cooperate with the parts which will now be described.

In carrying out our invention, we provide a transverse opening 8 through the car door adjacent to the rear lower corner of the car door. The opening 8 is enlarged or counterbored at its inner end as indicated at 9 and is adapted to receive a tubular latch casing 10. The tubular latch casing 10 is provided with an integral attaching plate portion 11 which is disposed flatwise against the outer face of the door 3 at the time the inner end portion of the casing 10 extends through the opening 8 into the counterbore

9. The attaching plate 11 is secured to the door 3 by suitable fastening devices, such as the bolt and nut indicated at 12.

10. The tubular latch casing 10 preferably extends an appreciable distance from the plane of the face of the outer plate 11 and is reduced in diameter adjacent to its outer end, as indicated at 13. A latch bolt 14 extends through the tubular latch casing 10 and is slidably and rotatably supported by the inner wall of the reduced portion 13. The latch bolt 14 is longer than the retaining pin and extends at its opposite ends beyond the corresponding ends of the latch casing. A handle 15 extends from the outer end of the latch bolt 14 at an angle to the latter slightly less than 90° and bears against a laterally extending cam rib 16 on the upper part of the attaching plate 11.

11. The rib 16 terminates at one end almost directly above the outer end of the tubular casing 10 and decreases regularly in width from that end toward its other end so that the latch bolt 14 will be moved axially outward in the casing 10 when the handle 15 has been grasped and is swung upward in sliding contact with the cam rib 16 to upright position, as illustrated in Fig. 3. When the handle 15 swings downwardly or in a clockwise direction from the position shown in Figure 3, the latch bolt 14 will move axially inward from the position illustrated in Figure 3 to the position illustrated in Figure 2 in response to the action of an expansion spring 17 which is coiled about the latch bolt 14 between the reduced portion 13 of the latch casing and a washer 18 that is disposed on the latch bolt against a stop pin 19. When the handle 15 is in upright position as illustrated in Figure 3, an elongated latch lug or detent 20 which is removably secured to the locking bolt 14 at the inner end of the latter also will be disposed in upright position. At this time, the latch bolt 14 is in its outermost or retracted position in respect to the latch casing 10 and the latch lug or detent 20 will be disposed in the counterbore or recess 9. When the arm is swung in a clockwise direction, the latch bolt 14 moves axially inward and also turns in a clockwise direction through an arc of 90° . This will result in the moving of the latch lug 20 from the recess 9 beyond the plane of the inner face of the door 3 and the swinging of the latch lug 20 in a clockwise direction to position to enter a socket 21 in the side of the car body at the adjacent or rearward edge of the door opening. The socket 21 may be a recess or depression in the adjacent post 7 but preferably is a depressed portion of a plate 22 which is secured to the adjacent post 7 by screws 23 or like fastening devices. When the latch lug 20 is in engagement with the socket 21, as illustrated in Figure 2, the handle 15 will

be disposed substantially in horizontal position and in contact with the cam rib 16 at the narrower end of the latter. The handle 15 may be secured to the cam rib in this position by any suitable known fastening means, such as the usual car seals, not shown, which may be threaded through openings 24 and 25 in the handle 15 and the cam rib 16 respectively and then may have the end portions thereof secured together in the usual manner.

From the foregoing description of the various parts of the device, the operation thereof may be readily understood. It will be obvious that the car door 3 will be held against moving from closed position when the detent or latch lug 20 at the inner end of the latch bolt is engaged with the socket 21. Moreover, since the door 3 is locked in the manner described to the fixed post 7 and therefore to the car body at a point adjacent to both the rearward edge and the lower end of the car door, the latter will be held securely against the outer face of the adjacent portion of the side wall of the car body without there being any necessity of providing the usual fastening cleats or battens in order to hold the car door close at its rearward edge of the car body. It also will be apparent that it will be extremely difficult for an unauthorized person to gain access to the exterior of the car by inserting a lever or other tool between the rearward edge portion of the car door and the car body preliminarily to forcing the rear edge portion of the car door outward from the car body since the engagement of the detent 20 with the socket 21 will tend to hold the car door so close to the car body that no space will be provided for the insertion of a tool of any size between the car door and the car body even though the underlying guiding and retaining bracket 6 shall have been removed.

When the latch bolt is in retracted or non-latching position, the inner end of the latch bolt and the detent 20 will clear the outer face or side wall of the car body when the car door moves from closed to its fully open position or vice versa. However, after the handle 15 has been released after having been moved to upright position to effect retraction of the latch bolt and the door 3 has been moved from fully closed position, the action of gravity on the handle 15 and of the spring 17 on the latch bolt will tend to cause the handle 15 to swing in a clockwise direction with consequent projection of the latch bolt axially inward toward latching position. This axial movement of the latch bolt inward will cause the detent 20 to move into contact with the wear plate or bar 6' when the door 3 is in any position between fully closed position and fully open position. The detent 20 will slide in contact with the

wear bar 6' and should the door move to fully closed position after having been latched in a partly open position, the detent 20 will drop into the socket 21 automatically and the door then will be held against swinging idly and in closed position until the detent 20 has been moved as a result of manual actuation of the handle 15 out of engagement with the socket 21. Should the door 3 move from partly open position to fully open position, the detent 20 will drop into a socket 26 which is suitably located in the side wall of the car body at the rearward end of the wear bar 6' and the car door then will be held against idle movement from fully opened position. Continued sliding of the car door equipped with our invention back and forth between open and closed positions when the car is in movement thus is precluded, since, if a car door equipped with our invention be left in partly open position, the first shock to which the car will be subjected in service will result in the car door moving either to fully closed or fully open 25 position and our latching device then would function to prevent any further movement of the car door relatively to the car body until the latch bolt has manually operated to effect release of the car door from the car body.

Another important advantage of our invention results from the fact that our latch is so constructed and the cooperative elements comprised in the latch and carried by the car body are so positioned in respect to each other that neither the latch bolt nor the keeper or socket member is under tensile stress when the door is retained against movement relatively to the car body, the stress tending to move the car door from the position in which it is retained being in the nature of a shearing stress on the latch bolt and not tending to cause the latch bolt to disengage the cooperative keeper, as is the case in ordinary latch constructions of which we are aware.

The handle 15 rests adjacent to its outer end on a lateral stop projection carried by the plate 11 and located at the narrower end of the cam rib 16 when the handle is in downwardly swung or substantially horizontal position.

Obviously, our invention is susceptible of embodiment in forms other than that illustrated in the accompanying drawings and we therefore consider as our own all such modifications and adaptations of the form of the device herein disclosed as fairly fall within the scope of the appended claims.

We claim:

1. A latch for car doors, comprising a tubular casing adapted to be positioned in a transverse opening in a car door, a latch bolt supported by the tubular casing for axial movement to and from position to ex-

tend beyond the inner face of the car door, a handle at the outer end of the latch bolt, spring means urging said latch bolt continuously toward position to extend beyond the inner face of the car door, and cooperative stop elements respectively carried by said latch bolt and said latch casing for limiting the movement of said latch bolt in response to the actuation of said spring.

2. A latch comprising a tubular casing, a latch bolt extending through the bore of the tubular casing, said latch bolt being of greater length than the casing and being adapted to slide and rotate in the latter, said latch bolt having a laterally extending handle portion at the outer end thereof, and a cam rib associated with the tubular position and against which the handle slides when the handle is swung in one direction, whereby the latch bolt will be moved outward in the tubular casing.

3. A latch comprising a tubular casing, a latch bolt extending through the bore of the tubular casing, said latch bolt being of greater length than the casing and being adapted to slide and rotate in the latter, said latch bolt having a laterally extending handle portion at the outer end thereof, a cam rib associated with the tubular position and against which the handle slides when the handle is swung in one direction, whereby the latch bolt will be moved outward in the tubular casing, and spring means tending to urge said latch bolt inward in the latch casing.

4. A latch comprising a tubular casing, a latch bolt extending through the bore of the tubular casing, said latch bolt being of greater length than the casing and being adapted to slide and rotate in the latter, said latch bolt having a laterally extending handle portion at the outer end thereof, a cam rib associated with the tubular position and against which the handle slides when the handle is swung in one direction, whereby the latch bolt will be moved outward in the tubular casing, spring means tending to urge said latch bolt inward in the latch casing, and a laterally extending detent at the inner end of the latch bolt, said handle portion and said detent extending laterally of the same side of the latch bolt.

5. A latch comprising a tubular casing, a latch bolt extending through the bore of the tubular casing, said latch bolt being of greater length than the casing and being adapted to slide and rotate in the latter, said latch bolt having a laterally extending handle portion at the outer end thereof, a cam rib associated with the tubular position and against which the handle slides when the handle is swung in one direction, whereby the latch bolt will be moved outward in the tubular casing, spring means tending to urge said latch bolt inward in the latch cas-

ing, and a stop at one end of said cam rib for limiting the swinging movement of the handle in contact with the rib.

6. The combination with a sliding car door having an opening formed therethrough adjacent to its rearward lower corner of a tubular casing disposed in said opening, a spring latch bolt rotatably and slidably supported in the bore of said casing and being of greater length than the casing,

said latch bolt being spring pressed axially inward continuously and having a detent portion at its inner end for engaging with a socket in a fixed part of the car body when the car door is in a certain position with respect to the car body, and a handle at the outer end of said latch bolt. 15
